UNITED STATES PATENT OFFICE.

WILTON H. PERRY, OF BROOKLYN, NEW YORK.

BOTTLE AND CLOSURE THEREFOR.

Application filed December 20, 1926. Serial No. 155,786.

This invention relates to bottles for containing ink, mucilage and other adhesives. The primary object of the invention is to provide a simple construction and a novel construction whereby ink and adhesives may be maintained against evaporation for long periods. It is well recognized that when ink is left in an inkwell for any appreciable time, evaporation takes place rapidly and 10 the ink becomes heavy and gummy and will not properly flow from a pen point or fountain pen. Furthermore, this evaporation constitutes a considerable factor of waste. Similarly, when mucilage or other adhesives 15 are left in bottles or wells without tight corks or stoppers, the adhesive becomes heavy and pastelike and will not properly spread.

The present invention provides a bottle or 20 well embodying a novel form of cover or closure and beneath which the mouth of the bottle is formed to provide an annular channel adapted to contain water which may be introduced from time to time to insure a 25 supply of water in the channel at all times. The cover may be provided on its under side with an absorbent pad which is adapted to be kept moist by the water in the channel or the pad may, in practice, be omitted and 30 the moisture given off by the water permitted to permeate all portions of the well or bottle in such manner as to maintain a substantially saturated atmosphere which will preclude evaporation or drying up of 35 the contents of the bottle or well.

In practically carrying out the invention, the bottle is provided with a somewhat larger neck than usual and this neck is formed with an axial opening to permit a 40 pen or brush to be introduced into the bottle. About this opening is formed an annular channel, the outer peripheral wall of which is somewhat lower than the inner peripheral wall and into this channel water 45 is adapted to be introduced. The difference in the height of these walls precludes the water from flowing into the bottle in the event that the channel is inadvertently filled to overflowing.

50 When incorporating the invention in bottles for use with adhesives, the bottle is provided with a cover preferably having an absorbent pad on its under side and the center of this pad and cover are cut away so 55 that a brush may be introduced through the cover and through the pad into the confines

of the bottle. The pad, however, is adapted to rest upon and form a closure for the open top of the water channel, so that the bottle may be carried about without danger of 60 spilling the contents thereof. The brush is preferably formed with a handle having a plug at its base which is adapted to serve as a cork for the central opening of the cover.

When employing the invention in conjunction with an ink bottle, the inner peripheral wall of the channel is preferably extended downwardly to substantially the base of the bottle to form a supplemental well and in this well a hollow sphere is adapted to be 70 positioned to facilitate the charging of a pen with ink as will be hereinafter more fully explained.

The cover employed on the ink bottle preferably embodies a suitable cap permanently mounted on the bottle and having a central opening registering with the supplemental wall. With this cap is associated a hinged cover provided on its under side with a pad which forms a tight seal for the opening in the cap and also may be utilized as a pen wiper. The cap is also preferably provided with an opening in its top juxtaposed with the water channel, so that water may be introduced into the channel without removing the cap. The pad on the cover is sufficiently extensive to overlie this opening when the cover is closed. Bottles embodying the present invention are simple in construction and will preserve the ink and adhesive without deterioration or evaporation through long periods.

Features of the invention, other than those specified, will be apparent from the hereinafter detailed description and claims, 95 when read in conjunction with the accompanying drawings.

The accompanying drawings illustrate different practical embodiments of the invention, but the constructions therein shown 100 are to be understood as illustrative, only, and not as defining the limits of the invention.

Figure 1 is a central section of an ink bottle embodying the present invention; 105 and,

Figure 2 is a like section of an adhesive bottle embodying the invention in a modified form.

Referring to the drawings, 1 designates a 110 bottle generally. This bottle is, in practice, preferably made relatively shallow and

is of a type adapted to contain ink. The neck of the bottle is made somewhat larger than usual and is provided interiorly with an annular channel 2 formed between upright standing cylinders 3 and 4 arranged coaxially of one another and with the bottle. It will be noted that the wall 4 is somewhat higher than the wall 3, so that when the water is poured into the channel, the water will not flow into the bottle if too much water is introduced, but will merely overflow the wall 3 and flow down and over the outside of the bottle. The wall 4 is extended downwardly beyond the base 5 of the channel as shown at 4^a to form within the confines of the bottle a supplemental well. This wall 4^a preferably terminates adjacent the bottom of the bottle, with sufficient clearance therefrom to permit ink to readily flow from the body of the bottle into the supplemental well.

Positioned within the supplemental well is a buoyant member 6 preferably in the form of a hollow ball which, in practice, is adapted to float upon the ink after the manner shown in full lines in Figure 1. The float 6 is of such size that if downward pressure is suddenly applied to the float ink will be caused to spurt upwardly around the periphery of the float and be deposited upon a pen point utilized to depress the float. Thus, when a pen is dipped into the well, it engages the float and upon slight downward pressure of the float by the pen, the ink will be caused to spurt as described and thus charge the pen without actually necessitating the dipping of the pen into the ink. I find this method of charging the pen highly economical from the standpoint of ink consumed, and, furthermore, the pen itself does not become overcharged with ink by this method, as it is very apt to do if it is dipped too deeply.

Permanently secured to the neck of the bottle is a cap 7 provided with a depending skirt 8, which embraces the neck of the bottle and holds the cap in position and having a top plate 9 which, in practice, is preferably flat. The cap is provided with a central opening 10 which registers with the supplemental well and with a further opening 11 overlying the channel 2.

Preferably pivoted to the cap 7 is a cover 12 having a hinged connection 13 with the cap and this cover may have a suitable knob or handle 14 whereby it may be readily manipulated. The under side of the cover carries a pad 15 of felt or other suitable absorbent material which, when the cover is closed, rests upon the flat top of the cap and seals both of the openings 10 and 11. The cover 12 may conveniently be made of sheet metal and its edge flanged in as shown to hold the pad in place.

When the ink bottle is not in use, the

cover is closed as shown in Figure 1, and the water contained in the channel will maintain a humid condition within the bottle which will preclude deterioration or evaporation of the ink. When it is desired to use the ink, the cover is raised to permit the pen to be introduced into the supplemental well through the opening 10. Water may be introduced as required through the opening 11 and if desired the skirt 8 of the cap may be provided with an overflow opening for the water at about the level of the upper edge of the wall 3, so that in the event too much water is introduced, it will exit through the overflow and not flow into the supplemental well.

In order to permit practically a total exhaustion of the ink from the bottle, the central portion of the bottom is preferably depressed as shown at 16, and the float 6 may descend to the position shown in dotted lines in Figure 1 to permit the last bit of ink to be exhausted by the float in the manner described. Legs or an annular ring 17 are preferably formed on the bottom of the bottle so that the bottle will sit solid on a desk or other support.

The structure of Figure 2 is well adapted for use as a mucilage bottle. Here the supplemental well may be incorporated, but it is not essential. The bottle 1^a of Figure 2 is provided with the channel 2 having an outer wall 3 and an inner wall 4. The cap 12 is similar to the cap 7 of Figure 1, except that the hole 11 of the latter cap is not required. A pad 15 of absorbent material is positioned within the cap 12, which in this embodiment of the invention may be readily removed from the bottle and this pad is shaped to sit upon the upper edges of the walls 3 and 4 and form a closure for the channel 2.

The opening 10^a in the cap of Figure 2 is preferably formed by flanging the central portion of the cap to provide a tapered opening, as shown. Into this tapered opening is adapted to be received a tapered stopper 18 preferably in the form of a pad of felt or other absorbent material. This stopper is carried by the handle 19 of a brush 20 and the base of said handle is preferably flanged as shown at 21 to keep the stopper from being pressed too tightly into the opening 10^a. The flange about the opening in the center of the cap protects the pad 15 from coming into contact with the brush when said brush is inserted into or removed from said bottle.

In either form of the invention which I have described, water in the channel 2 serves to humidify the interior of the bottle. In the construction of Figure 1, the top of the channel is opened and the moisture rising from the water in the channel is allowed to circulate freely throughout the bottle.

In the construction of Figure 2, however, the moisture rising from the water in the channel is absorbed by the pad 15 which is thereby maintained at all times in a wet or 5 damp condition and serves, in turn, to humidify the interior of the bottle. It will of course be understood that the bottles of the present invention may be made from any suitable material and this applies likewise to 10 the covers and closures thereof. They may be manufactured economically and will function with high efficiency in maintaining ink or adhesives without deterioration for long periods of time.

15 The air vent 22 shown in Fig. 1 is to permit the escape of air from the body of the container when filling the container with ink.

Having thus fully described the invention, 20 what I claim as new and desire to secure by Letters Patent is:

1. A bottle provided in the top of its neck

with an annular channel adapted to contain water and surrounding the mouth of the bottle, a cap fitted on to the neck of the bottle 25 and covering the top of said neck with that portion of the cap which overlies the neck spaced from the top of the neck and provided with an opening registering with the mouth of the bottle, a cover for said cap 30 and adapted when in closed position to seal the opening in the cap, and a pad of absorbent material carried by the cover on the under side thereof.

2. A bottle provided in the top of the 35 neck with a water channel surrounding the mouth of the bottle and adapted to contain water, a cap fitted over the neck and provided with an opening juxtaposed with the mouth of the bottle, and an absorbent pad 40 above the mouth of the bottle.

In testimony whereof I have signed the foregoing specification.

WILTON H. PERRY.
